UNITED STATES PATENT OFFICE.

WILLIAM A. KING, OF MEMPHIS, TENNESSEE.

DESIGN FOR AN AUTOMOBILE BODY.

Application filed May 8, 1920. Serial No. 379,981. Term of patent 14 years.

To all whom it may concern:

Be it known that I, WILLIAM A. KING, a citizen of the United States, residing at Memphis, in the county of Shelby and State of Tennessee, have invented a certain new, original, and ornamental Design for an Automobile Body, of which the following is a specification.

Figure 1 is a view of the new and ornamental car body in side elevation,

Figure 2 is a top plan view of the body,

Figure 3 is a view of the body in rear elevation,

Figure 4 is a view of the body in front elevation.

This drawing illustrates an automobile body of my new and ornamental design.

I claim,

The ornamental design for an automobile body as shown and described.

In witness whereof, I have hereunto set my hand and seal at Memphis, Tennessee, this 22 day of April, A. D. nineteen hundred and twenty.

WILLIAM A. KING. [L. s.]
